UNITED STATES PATENT OFFICE.

STANISLAW MACKIEWICZ, OF WORTMAN, COLORADO.

TOILET ARTICLE.

1,298,750.

Specification of Letters Patent. Patented Apr. 1, 1919.

Application filed June 13, 1918. Serial No. 239,784.

To all whom it may concern:

Be it known that I, STANISLAW MACKIEWICZ, a citizen of Poland, residing at Wortman, in the county of Lake and State 5 of Colorado, have invented certain new and useful Improvements in Toilet Articles, of which the following is a specification.

This invention relates to the toilet, and more especially to toilet cases; and the object of the same is to produce a combined 10 article which will include a comb, a brush, and a mirror.

Another object is to produce a cover for holding the several articles together and for 15 protecting the bristles of the brush and also the clothing from the bristles, as well as protecting the face of the mirror.

Other objects will appear in the following specification and claim, and attention is 20 directed to the drawings wherein:

Figure 1 is a vertical section through the casing and an edge view of the parts of this device assembled,

Fig. 2 is an elevation of one part with 25 half the casing removed, and

Fig. 3 is a sectional view of this part alone.

The bristles of the brush are indicated as 1, and the back 2 is continued into a handle 30 3 which has the usual configuration on its front side but is cut off flat on its rear side as seen in Fig. 1. The mirror 4 is inset into a back 5 which is continued into a handle 6 rounded on its forward side and cut off flat 35 on its rear side so as to complement the handle 3 of the brush as seen in Fig. 1. Therefore when these two parts come together, the handle has the usual configuration. In the flat rear face of the back 5 and 40 handle 6 of the mirror part of this device, is a channel 7 adapted for reception of the comb 8 as seen in Fig. 2, and pivotally mounted on the back 5 of the mirror part is a support 9 of the usual formation so that 45 the mirror may be stood up on the table. Attention is invited to the fact that a thumb notch 19 permits opening of the support and

a thumb notch 17 permits the removal of the comb from the channel 7. Also the back 5 is recessed as at 15 for the reception of the 50 support 9 so that it lies therein as indicated in dotted lines in Fig. 3.

Finally a casing incloses the head of the brush and the glass of the mirror. This casing is in two parts 20 and 21 which are 55 hingedly connected at one edge as indicated at 22, and are latched at the other edge as indicated at 23, one part being omitted from Fig. 2 entirely. The parts merge into complementary necks 24 and 25 which when 60 brought together closely surround the combination handle 3—6 so as to hold the brush element and the mirror element together as long as the casing is latched. The casing also closely incloses the brush and the mirror and 65 protects these articles from other articles within the trunk or protects other articles from these articles. Finally the casing of course locks the two parts of the device together and closes the channel within which 70 the comb is located, and therefore this element cannot become lost. The parts are of the desired sizes, shapes, proportions and materials, and changes in details and in design can be made without departing from 75 the principle of my invention.

Having thus fully described my invention, what I claim as new and desire to secure by Letters Patent, is:

A combination toilet article including a 80 brush whose back and handle are flat on their rear faces, a mirror whose back and handle are also flat on their rear faces but provided with a longitudinal channel for a comb and a recess around the upper end of the channel, 85 a mirror support pivoted within said recess, and means for holding the elements together with their flat faces in contact.

In testimony whereof I affix my signature in presence of two witnesses.

STANISLAW MACKIEWICZ.
